[57] CLAIM

We claim the ornamental design for a handle for sponge applicator, as shown.

DESCRIPTION

FIG. 1 is a top plan view of the handle for sponge applicator showing our new design;

FIG. 2 is a right side elevational view thereof;

FIG. 3 is a bottom plan view thereof;

FIG. 4 is a left side elevational view thereof;

FIG. 5 is a perspective view thereof;

FIG. 6 is an elevational view taken from the sponge connecting end; and,

FIG. 7 is an elevational view taken from the hook shaped hand grip end thereof.
